[57] ABSTRACT

Expansible mandrels are disclosed for use in driving or withdrawing tubular piles and the like, said mandrels comprising sections with a head connected to and joining their upper ends, and with at least one means below said head operable to vary the spacing of the mandrel sections between pile-entering and pile-gripping relationships. The operating means include a plurality of members within the mandrel and spaced lengthwise thereof, flexible means in trained engagement with the members and operable on a pull thereon in a predetermined direction to move the members in predetermined directions, and force-transmitting connections between the members and the mandrel sections to transmit opposite transverse forces thereto urging them into one of said relationships on such movement of the members. The pull on the flexible means is established in effecting either one or both operative relationships by power operated means.

EXPANSIBLE MANDRELS FOR USE IN DRIVING OR WITHDRAWING TUBULAR PILES

The present invention relates to expandable mandrels for use in driving or withdrawing tubular piles and the like. The present application is a continuation-in-part of our copending application, Ser. No. 824,631, filed May 14, 1969 now abandoned.

BACKGROUND OF THE INVENTION

In order that a tubular pile can be driven into the ground, it must be secured to a mandrel that can absorb the hammer energy that would damage a tubular pile under usual conditions if applied directly thereto. Expandable mandrels have been provided with means for expanding them from a contracted, pile-entering relationship into an expanded, pile-gripping relationship. Both the use of mechanically operated linkage and inflatable members have been employed.

The difficulty with such mandrels is that mechanically operated proposals have not been capable of applying sufficient pile-gripping force with controlled distribution throughout the length of a pile to insure satisfactory operation and proposals utilizing fluid under pressure have not been economical.

SUMMARY OF THE INVENTION

The general objective of the invention is to provide expandable mandrels that overcome the generally stated short-comings of prior proposals and in accordance with the invention, this general objective is met by providing an expandable mandrel having sections connected at their upper ends by a head and provided with operating means below the head operable to effect the spacing of the sections between pile-entering and pile-gripping relationships. The operating means includes a plurality of members within the mandrel and spaced lengthwise thereof, flexible operating means in trained engagement with the members and operable on a pull thereon in one direction to move the members in one direction to move the members in predetermined directions, and force-transmitting connections between the members and mandrel sections to transmit opposite transverse forces on the mandrel sections urging the sections into one of the above referred to relationships on such movements of the members. The members of the two series are arranged in groups and each group may have its own flexible means or the flexible means may be common to a series of groups.

In one embodiment of the invention hereinafter sometimes referred to as the first type, the members are arranged in two series, one series for each mandrel section. The members are arranged in groups in which the members of one series alternate with those of the other series and the groups are spaced lengthwise of the mandrel. The trained engagement of the flexible means is with the members of each group in succession and the members are so disposed transversely of the mandrel sections and so dimensioned that the trained engagement of the flexible means is sinuous whereby the sections are forced into one of their relationships as a pull on the flexible means straightens it. When the portions of the members of each mandrel section with which the flexible means is in trained engagement are within the other section, the lateral force resulting from a lengthwise pull on the flexible means urges the sections apart into their pile-gripping relationship. When the portions

with which the flexible means is in trained engagement are within the mandrel sections to which they apply force and the members of the two series are connected to the appropriate mandrel section, a lengthwise pull on the flexible means results in lateral forces being applied through the members that urge the sections into their pile-entering relationship. The members may be fixed or rotatable and some of the members of each series may be movable lengthwise of the sections within limits and the flexible means may consist of one or more cables, bands, wire ropes, chains or combinations thereof.

Particular objectives of the invention are concerned with the provision of connections that will facilitate assembly and service of the members without dismantling other adjacent members.

Another objective of the invention is to provide an expandable mandrel in which the operating means include toggle joints to effect either one or both of the relationships of the mandrel sections, expandable mandrels operating on this basis being sometimes referred to as those of the "second type." This objective is attained by providing members that are sheaves and the force-transmitting connections are toggle joints each of which rotatably supports a sheave and has each of its two links pivotally connected to the appropriate mandrel section. The toggle joints are arranged in oppositely disposed pairs so that with the flexible means, desirably a cable trained about their sheaves, those sheaves are drawn together by a lengthwise pull thereon with the toggle joints applying force urging the sections into one of their relationships. Where both relationships are to be established by toggle joint-sheave arrangements, a second cable is employed and is trained about the proximate sheaves of proximate pairs of toggle joints and is operative to draw them towards each other to effect the other relationship of the mandrel section.

Another objective of the invention is to provide toggle joint-sheave units that facilitate assembly and service without dismantling the adjacent units.

Another objective of the invention is to provide a toggle joint, for use in either type of mandrel, interconnecting the mandrel sections at their bottom ends and actuated by a sheave in response to a pull on flexible means trained about it, the flexible means preferably being that actuating the operating means to provide the pile-gripping relationship of the mandrel sections and serving to enable at least one course to extend the full length of the mandrel without being interfered with by the members and its other course to be disposed about the member in the appropriate manner.

Yet another objective of the invention is to provide resilient means for effecting one of the operative relationships with the means for effecting the other relationship being actuated by flexible means and either of the first type in which the members are moved transversely or of the second type in which they are moved lengthwise of the mandrel.

Other objectives are concerned with the construction of mandrel sections providing lengthwise reinforcements and the connections between the members and the mandrel sections, and with means enabling the mandrel-expanding forces to be distributed and applied as desired lengthwise of the mandrel.

Yet another objective of the invention is to provide means, for use with either type, for exerting a pull on

the flexible means of a desired magnitude in establishing either one or both of the relationships between the mandrel sections, an objective attained by means of a power operated unit, preferably a fluid pressure operated piston-cylinder unit within the upper part of the mandrel and supported therein either by the sections or by the drive head.

Another objective of the invention is to provide expansible mandrels with a series of fluid pressure operated units, each in charge of at least one group of members and spaced lengthwise of each other not only to minimize frictional problems but also to make possible expansible mandrels wherein expanding forces are applied progressively from bottom to top and a particular objective is to provide, when a pull on the flexible means effects the pile-gripping relationship of the mandrel, that each unit also operates means to effect their other relationship.

A further objective of the invention is to provide expansible mandrels whose sections require a minimum amount of welding, an objective attained, where a pull on the flexible means results in the pile-gripping relationship of the mandrel sections, in one embodiment, by suspending the members within the mandrel and in another embodiment, by positioning a cannister within the mandrel, the cannister including sections, one for each mandrel section and the cannister containing the operating means.

THE DRAWINGS

FIG. 1 is a section taken lengthwise of an expansible mandrel in accordance with one embodiment of the invention with certain elements schematically shown, the operating means being shown on a schematic basis;

FIG. 1A is a section of the drive head end of the mandrel with the mandrel turned 90° from its FIG. 1 position;

FIG. 1B is a fragmentary lengthwise section showing one of the anchored ends of the flexible means by which the mandrel is expanded;

FIG. 1C is a diagram illustrating a desired distribution of the mandrel expanding forces;

FIG. 2 is a section showing the mandrel head or top and the connections between it, the upper end of the mandrel, and the hydraulic unit;

FIG. 3 is an edge view of the toggle joint-sheave unit interconnecting lower ends of the mandrel sections;

FIG. 4 is a face view of the toggle joint-sheave unit;

FIG. 5 is a section taken transversely of the mandrel, the section being taken through the sheave by which the toggle joint is actuated;

FIG. 6 is a section transversely of the mandrel, the section being taken through the pivotal connection between the links of the toggle joint and the mandrel sections;

FIG. 7 is a plan view of a length of a mandrel section, inclusive of one of the groups of members, the members being shown as sheaves, and showing the marginal reinforcements of one sheave carrier of that section attached thereto;

FIG. 8 is a section taken along approximately the lines 8-8 of FIG. 7;

FIG. 9 is a section taken transversely of the mandrel through a central sheave;

FIG. 10 is a section taken lengthwise of the mandrel through one of the groups of members in accordance with another embodiment of the invention;

FIG. 11 is a section taken approximately along the indicated lines 11-11 of FIG. 10;

FIG. 12 is a partly sectioned, elevated view of a mandrel in accordance with another embodiment of the invention, the section being taken approximately along the indicated lines 12-12 of FIG. 13 but with the sheaves and cables shown in elevation;

FIG. 13 is a section taken approximately along the indicated lines 13-13 of FIG. 12;

FIG. 14 is a section taken approximately along the indicated lines 14-14 of FIG. 12;

FIG. 15 is a partly sectioned view of the lower end of a mandrel section illustrating a toggle joint-sheave unit in accordance with another embodiment of the invention;

FIG. 16 is a section taken approximately along the indicated lines 16-16 of FIG. 15;

FIG. 17 is a section taken approximately along the indicated lines 17-17 of FIG. 16;

FIG. 18 is a section taken transversely of a mandrel in accordance with another embodiment of the invention in which the mandrel sections are urged into their pile-gripping relationship by a series of compression springs and retracted by cable actuated sheaves;

FIG. 19 is a like section but with the mandrel sections in their expanded relationship;

FIG. 20 is a view similar to FIG. 1 illustrating somewhat schematically an expansible mandrel in accordance with another embodiment of the invention in which the connecting means comprises sheaves arranged in pairs with each sheave operating a toggle joint;

FIG. 21 is a section taken lengthwise of the mandrel of FIG. 20 to show one of the toggle joint-sheave units;

FIG. 22 is a section taken approximately along the indicated lines 22-22 of FIG. 21;

FIG. 23 is a section taken approximately along the indicated lines 23-23 of FIG. 21;

FIG. 24 is a cross section through an expansible mandrel showing a connection between the bottom ends of the mandrel section in accordance with another embodiment of the invention in which the pile-gripping relationship is effected by a toggle joint-sheave unit and the pile-entering relationship is effected by springs;

FIG. 25 is a section taken approximately along the indicated lines 25-25 of FIG. 24;

FIG. 26 is a somewhat schematic fragmentary view of a mandrel in accordance with yet another embodiment of the invention in which the mandrel sections are interconnected by a series of pairs of toggle joints, each actuated by a lengthwise movement of a sheave about which one cable is trained in a manner effecting the pile-gripping relationship of the mandrel sections and about which another cable is trained in a different manner to effect the pile-entering relationship thereof, FIG. 26 showing only the disposition of the first named cable;

FIG. 26A is a like view but showing only the disposition of the second named cable;

FIG. 27 is a plan view of the adjacent sheaves of an adjacent pair of toggle joint-sheave units of the mandrel illustrated by FIGS. 26 and 26A;

FIG. 28 is a like view of the bottom sheave and the adjacent sheave of the adjacent pairs of toggle joint-sheave units;

FIG. 29 is a section through the mandrel illustrating the modified form of mandrel sections;

FIG. 30 is a view, similar to FIGS. 1 and 20, illustrating somewhat schematically an embodiment of the invention in which there is a series of operating means each having its own power operated unit;

FIG. 31 is a fragmentary section taken longitudinally of the mandrel of FIG. 30 in its pile-entering relationship of its sections with the members rotatable bushings and the flexible means a roller chain;

FIG. 32 is a like view but with the mandrel sections in their pile-gripping relationship;

FIG. 33 is a section taken along the indicated lines 33—33 of FIG. 31;

FIG. 34 is a like view but with the mandrel sections in their pile-gripping relationship;

FIG. 35 is a section, similar to FIG. 31, but with the members spherical, the flexible means a roller chain, and the carriers for the members provided with spring-backed followers;

FIG. 36 is a plan view of one of the mandrel sections of the embodiment of the invention shown in FIG. 35;

FIG. 37 is a section taken approximately along the lines 37—37 of FIG. 35;

FIG. 38 is a section similar to FIG. 37 but with the mandrel sections in their pile-gripping relationship;

FIG. 39 is another fragmentary longitudinal section of a mandrel in which the members are fixed sheaves and the flexible means is a wire rope;

FIG. 40 is a like view but with the mandrel sections in their pile-gripping relationship;

FIG. 41 is a section taken along the indicated lines 41—41 of FIG. 39;

FIG. 42 is a section taken along the lines 42—42 of FIG. 40;

FIG. 43 is a fragmentary section taken longitudinally of the mandrel showing a group of members having spherical rims and the flexible means a chain entrant of a groove with which each rim is provided, the end members being fixed and the intermediate members free to travel relative thereto;

FIG. 44 is a like view but with the mandrel sections in their pile-entering relationship;

FIG. 45 is a section taken along the indicated lines 45—45 of FIG. 43;

FIG. 46 is a section taken along the indicated lines 46—46 of FIG. 44;

FIG. 47 is a fragmentary longitudinal section of a mandrel in which the members are multi-grooved sheaves and the flexible means comprises four parallel wire ropes;

FIG. 48 is a section taken approximately along the indicated lines 48—48 of FIG. 47;

FIG. 49 is a like view but showing a divided sheave;

FIG. 50 is a like section illustrating an embodiment of the invention in which the flexible means is a belt in trained engagement with a pulley;

FIG. 51 is another longitudinal, fragmentary section of an expandible mandrel showing one end of a flexible means comprising a plurality of parallel wire ropes trained over fixed sheaves;

FIG. 52 is a section taken approximately along the indicated lines 52—52 of FIG. 51;

FIG. 53 is a fragmentary, longitudinal section of the lower end of the embodiment of the invention in which the flexible means is a pair of heavy-duty chains;

FIG. 54 is a section taken along the indicated lines 54—54 of FIG. 57;

FIG. 55 is a fragmentary, longitudinal section of the upper portion of an expandible mandrel in accordance with another embodiment of the invention;

FIG. 56 is a like view of the lower end of the mandrel shown in FIG. 53;

FIG. 57 is a section taken approximately along the indicated lines 55—55 of FIG. 53;

FIG. 58 is a section taken approximately along the indicated lines 56—56 of FIG. 54;

FIG. 59 is a longitudinal section through the lower end of a modification of the mandrel illustrated by FIGS. 53—56;

FIG. 60 is a section taken approximately along the indicated lines 58—58 of FIG. 57;

FIG. 61 is a view similar to FIGS. 1, 20, and 30 illustrating another first type expandible mandrel;

FIG. 62 is a fragmentary, lengthwise section through the sections at the lower end of another mandrel;

FIG. 63 is a section taken approximately along the indicated lines 63—63 of FIG. 62;

FIG. 64 is a fragmentary plan view of one of the mandrel sections;

FIG. 65 is another fragmentary, longitudinal section of the lower part of a mandrel of the type schematically illustrated by FIG. 61;

FIG. 66 is a section taken approximately along the indicated lines 66—66 of FIG. 65;

FIG. 67 is a section taken approximately along the indicated lines 67—67 of FIG. 65;

FIG. 68 is a fragmentary, longitudinal section of an expandible mandrel in which the carriers of the members of a group are attached to a common, suspended mount and the flexible means is a pair of chains;

FIG. 69 is a section taken approximately along the indicated lines 70—70 of FIG. 69;

FIG. 70 is a fragmentary plan view of a mandrel section provided with sheave carrier locating seats; and

FIG. 71 is a section through one of the seats illustrating a sheave carrier being entered therein.

In the embodiment of the invention illustrated by FIG. 1, the expandible mandrel is shown as consisting of a pair of arcuate sections 30, each of substantial length and of an arcuate extent sufficiently less than 180° so that when the sections are close together, the mandrel may be entered into a tubular pile of a particular diameter and tightly grip that pile when the mandrel sections are forced apart to a predetermined maximum extent. The mandrel sections 30 have ribs 31, spaced and arranged for mating engagement therein or for positive gripping engagement with other tubular piles. The ribs 31 may be transverse or helical and each merges into the mandrel section of which it is a part short of the edges thereof. The ribs 31 are close together at the lower portion of the mandrel and the distance between them increases towards the head end thereof. The use of such ribs is preferred in all embodiments of the invention, but with the exception of FIGS. 21—23, is shown only in views comparable to FIG. 1, namely, FIGS. 20, 26, and 26A.

The sections 30 are connected at their upper end by a generally indicated top or drive head 32, best seen in FIG. 2 and at their lower ends by a generally indicated toggle joint-sheave unit 33 schematically shown in FIG. 1 but detailed in FIGS. 3 - 6. The sections 30 are also connected together by operating means spaced lengthwise of the mandrel and including, as the flexible means, cables 34 and 35 to effect the pile-entering and pile-gripping relationships, respectively, of the mandrel sections. The operating means are generally indicated at 36 and shown schematically in FIG. 1 but are detailed in FIGS. 7 - 9.

While the drive head 32 may be of other types, it is shown, see FIG. 2, as including an upper part 37 having a concave socket 38 to receive the bevelled end of the cushion block 39 and provided with outwardly disposed ears 40 for use in attaching the head to the hammer. An aligning pad 41 is interposed between the socket 38 and the cushion block 39, the pad having its bottom face convex and its upper face flat. The drive head part 37 is also provided with an outwardly disposed flange 42 and a downwardly extending axial neck 43.

Each of the mandrel members 30 have a reinforcing section 44 welded to its upper end and each member and its reinforcement is welded to a split plate 45. An intermediate plate 46, a clamping ring 47, having a shoulder 48 to overlie the flange 42, and the plate sections 45 have vertically aligned bores to receive clamping bolts 49. Each bolt receiving bore of the ring 47 opens upwardly through a concave seat 50 for a convex washer 41 disposed between it and the nut 52 while washers 53 and 54 are disposed between the undersurface of the plate section 45 and the bolt heads, one mating face of the washers 53 and 54 being concave and the other convex. By these or equivalent means, small misalignments between the mandrel and the drive head and hammer are accommodated. It should be noted the mandrel sections 30 and their reinforcements are welded to the split plate section 45 so that when the plate sections 45 are attached to the head 32, the mandrel sections 30 are in a spaced apart relationship.

The cylinder 55 of a fluid-pressure operated unit has a holder 56 connected to its upper end by a pivot 57 and lashed by a cable 58 to a holder 59 fixed on the end of the neck 43. The piston rod 60 of the fluid-pressure operated unit has a carrier 61 fixed on its exposed end and provided with a sheave 62. The invention is herein discussed with the fluid pressure units being of either the air operated type or the hydraulically operated type.

The toggle joint-sheave unit 33 is detailed in FIGS. 3 - 6 and is shown as having two pairs of links 63, each pair being pivotally connected at one end as at 64 to the appropriate one of the ears 65 with which the lower extremities of the mandrel sections are provided. The other ends of the pairs of toggle links 63 are connected to the end of an actuator 66 by the appropriate one of the laterally spaced pivots 67. The actuator 66 is connected to a rectangular carrier 68 by a pivot 69, the carrier 68 having a pair of ears 70 in support of a bottom sheave 71. As may be seen in FIGS. 4 and 5, the sheave 71 is diagonally positioned. Upward movement of the sheave 71 is limited by stops 72 carried by the mandrel sections and engageable by the carrier 68.

As is apparent from FIG. 1, the operating means 35 includes a plurality of sheaves 73 and 74 arranged in

groups spaced lengthwise of the mandrel, the sheaves 73 being connected to one mandrel section 30 and the sheaves 74 being connected to the other mandrel section. The sheaves 73 and 74 are alternatively disposed and the number of sheaves in each group decreases towards the upper end of the mandrel. The diameter of the sheaves are desirably as large as can be accommodated within the mandrel when its sections are in their pile-entering relationship. Apart from the number of sheaves that a group has, they may be regarded as identical.

The expansion cable 35 is anchored as at 75 at one end through the upper end of one of the mandrel sections 30 and its reinforcement 44 and extend downwardly around the bottom sheave 71 and is then trained between the sheaves 73 and 74 of each group so that an upward pull on the cable 35 forces the sheaves 73 and 74 apart and, accordingly, forces the sections 30 into their pile-gripping relationship. It will be appreciated that the diagonal disposition of the sheave 71 enables the course between the sheave 71 and the anchor 75 to be at one side of the plane inclusive of the course trained between the sheaves 73, 74. The cables 35 is also trained about the sheave 62 and a sheave 76 that, see FIG. 1, is coaxial with the uppermost sheave 74 of the uppermost connecting means 36 and then is connected to the anchor 77, see FIG. 1B, with which one of the mandrel sections 30 is provided. With this disposition of the cable 35, the delivery of fluid under pressure to the cylinder 55 provides a pull urging the mandrel sections 30 into their pile-gripping relationship.

The retraction cable 34 is trained about the sheaves 73 and 74 of each group in a similar but opposite manner with one end anchored to the bottom end of one of the mandrel sections 30 as at 78 and its other end extending outwardly through the upper end of one of the mandrel sections 30 and its reinforcement 44 and trained through guide pulleys 79 and 80, see FIG. 1A, and shown as having a ring 81 for a hook, not shown, by which an upward pull may be provided that will result in the sections being drawn together to establish their pile-entering relationship. As less force is necessary to establish the pile-entering relationship than the pile-gripping relationship, not all the sheaves of all the connecting means 36 need to be employed. The retraction cable 34 may, of course, be actuated by a power operated unit like the fluid pressure operated unit actuating the expansion cable 35 or a double-acting power operated unit may serve both cables.

In the manufacture of mandrels in accordance with the invention, the attachment of the sheaves and toggle joints present a choice between utilizing mandrel sections that are relatively thick-walled or of reinforcing the mandrel sections that are relatively thin. In the latter case, internal reinforcements 82 are welded to each margin of both mandrel sections substantially throughout their length while in the former case their use may be limited, if used at all, to the support of the members, the toggle joint 33, or of the stops 72.

In FIGS. 7 - 9, one of the groups of members is detailed, the others being substantially identical except for the number of sheaves they contain. Each sheave is shown as supported by a frame 83 and is provided with ears 84 having transversely aligned bores 85 exposed, when the frame is secured in position in a mandrel section 30, above the sides of that section thereby to enable a sheave supporting pin 86 to be inserted there-

through and through a sheave 73 or 74 from one side of a mandrel section 30. Stops 86 are welded to each mandrel section, conveniently to the reinforcements 82, the stops 87 of one mandrel section confining a pin 86 in support of a sheave of the other section against any substantial axial movement. As may be seen in FIG. 9, vertically spaced members 88 and 89 are welded to each reinforcement and define a slideway 90 receiving the margins of the frames 83 and slidably supporting them until each is located therein by welding stops.

Another embodiment of the operating means is illustrated by FIGS. 10 and 11 and one of its groups of members is generally indicated at 36A. As the members 36 and 36A have many common features, the corresponding parts are identified by the same reference numerals but in the case of the connecting means 36A these are distinguished by the suffix addition "A".

In this embodiment of the invention, the members 88A and 89A are secured to the reinforcements 82A of each mandrel section 30A and define a slideway 90A, the slideways being arcuate in a lengthwise direction. Each of the frames 83A is similarly curved for sliding entry into its slideway 90 and its ears 84A have transversely aligned bores 85A exposed to enable a pin 86A to be inserted through them after the installation of the frames 83A and through a sheave from either side of the mandrel section 30A to which that frame is attached. Stops 87A and 91 are welded to the reinforcements 82A in each mandrel section, the stops 87A of one section confining the pins 86A for the support of the sheaves of the other section against unwanted axial movement and the stops 91 of one mandrel section, in the assembled mandrel, limiting the extent to which a frame 83A may travel in the slideway 90A of the other mandrel section 30A.

In FIGS. 12 - 14, yet another embodiment of the operating means is shown, the operating means being generally indicated at 36B and the parts of this embodiment that correspond to the previous embodiments of the operating means are distinguished by the suffix addition "B" to the appropriate reference numerals.

In this embodiment, it may be assumed that the mandrel sections 30B have a wall thickness such that the reinforcements 82B are only of a length required by each of the groups of members of the operating means 36B. Ears 84B are welded to their proximate faces with their bores 85B transversely aligned. It will be noted that the bores 85B are dimensioned to receive bushings 92 and split bushings 93 and their bores 85B are partly below the plane inclusive of the edges of the mandrel section when the bushings are inserted in the attached ears 84B. The bushings 92 and 93 include, at their outer ends inturned marginal shoulders 94 and 95, respectively, engageable by the ends of the pin 86B with the outer ends backed by the proximate faces of the reinforcements 82B of the sections 30B to which they are not connected. While each bushing 92 may be inserted into its bore 85B before a sheave 73B or 74B is inserted between the ears 84B, an identical bushing could not then be placed in position in the other bore of the opposite ear 84B. For that reason, the bushing 93 is formed by uniting two identical sections with their mating faces indicated at 96 in FIG. 13, and in mandrel assembly or service, first one bushing section is inserted in the appropriate bore 85B and turned into a pin-supporting position in which the other section of the bushing 93 can then be inserted. Both sections may

then be turned together to place them in a position in which they are both backed by the reinforcement 82B.

In FIGS. 15 - 17, there is shown another embodiment of the toggle joint interconnecting the bottom ends of the mandrel sections. The toggle joint is generally indicated at 33C and where parts shown in this embodiment are the same as those previously described they will be distinguished by the suffix addition "C" to the appropriate reference numeral.

In this embodiment of the invention, a boot 97 is secured to the bottom end of each mandrel section 30C and each of these slidably supports the ends of a pair of pins 98. Each pin 98 supports corresponding ends of a pair of toggle links 63C connected at their other ends to the actuator 66C by pivots 99. As in the case of the toggle joint 33, detailed in FIGS. 3, 4, 5, and 6, the actuator 66C is connected to a carrier 68C by a pivot 69C. A sheave 71C is pivotally supported between a pair of ears 70C with which the carrier 68C is provided.

It will be noted that the actuator 66C has laterally spaced holes 100, see FIG. 16, one for each pin 98, and the holes 100 are of a diameter substantially greater than that of said pins. It will be appreciated that when the cable 35C is subject to a pull urging the sections 30C into their expanded relationship, the actuator 66C functions to force the pins 98 apart until the links 63C are parallel thus limiting the extent to which the pile-entering end of the mandrel can be expanded.

In the previously discussed embodiments of the invention, it is assumed that both cables 34 and 35 are used. If only one cable or other flexible means is used to effect one relationship of the mandrel sections, the other relationship must be effected by other means.

In the embodiment of the invention illustrated by FIGS. 18 and 19, it is assumed that the cable 35 is not used. In this embodiment of the invention the operating means are indicated generally at 36D and as may be, in part, similar to those previously described, corresponding parts are distinguished by the suffix addition "D" to the appropriate reference numeral. Internal, welded reinforcements 100 marginally of the mandrel sections 30D have carriers 101 for the sheaves 73D, 74D bolted thereto as at 102. The reinforcements 100, first at one side of the assembled mandrel and then the other, are provided with transversely aligned sockets 103 backing opposite ends of compression springs 104 operable to force the mandrel sections 30D into their pile-gripping relationship when the retracting cable 34D is released, the retracting cable extending between the sheaves 73D and 74D of the connecting means 36D in the manner illustrated in FIG. 1. The cable 34D may be actuated either by a power operated unit within the mandrel or by means externally thereof. The resilient connections between the mandrel sections are spaced from each other lengthwise of the mandrel as required to insure the desired distribution of expanding forces.

In the embodiments of the invention as thus far described, the sheaves of the cable actuated connecting means have been forced laterally by flexible means in the form of a cable in effecting either one or both of the operative relationships of the mandrel sections. In FIGS. 20 - 23, an embodiment of the invention is shown wherein the sheaves are moved lengthwise of the mandrel in response to a pull on the cable, such movements of the sheaves actuating toggles.

In this embodiment of the invention, the operating means are indicated generally at 36E and parts that correspond to those previously described are distinguished by the suffix addition "E" to the appropriate reference numerals.

As may be seen in FIG. 20, the operating means 36E consists of a pair of toggle joints generally indicated at 105 and interconnecting the mandrel sections 30E and spaced lengthwise from each other by a distance that increases towards the upper end of the mandrel, each joint 105 of each pair being shown as disposed so that, on a pull towards the other joint of that pair, the sections 30E are forced into their pile-gripping relationship. Each toggle joint 105 is moved by a sheave means generally indicated at 106 and consisting of a coaxial pair of sheaves 107 and 108. The cable 35E is connected to one mandrel section 30E as at 75E and extends downwardly about one of the sheaves of the proximate sheave means 106 and about the sheave 62E carried by the piston rod 60E of the fluid pressure operated unit and then extends directly to the lower end of the mandrel where it is trained about the sheave 71E by which the toggle joint 33E is actuated and then is trained about the appropriate sheave of the two sheave means 106 of each pair of operating means 36E. The other end of the cable 35E is anchored as at 77E.

In FIGS. 21 - 23, one toggle joint-sheave unit of an operating means 36E is detailed and it will be understood that the other toggle joint-sheave unit of each pair is the same except that its toggle joint 105 is oppositely disposed. In FIGS. 22 and 23, one mandrel section 30E is shown in an expanded position to show certain details more clearly.

Each toggle joint 105 includes pairs of links 110, one pair for each mandrel section 30E and connected to mounts 111 therein by pivot pins 112. The mounts 111 are shown as welded to lengthwise marginal reinforcements 82E with each having a pocket 113 opening through its inner edge and inclined outwardly in a direction towards the other toggle joint 105 of a pair, the pockets 113 of each mandrel section 30E being transversely aligned to slidably receive the pins 112. The other ends of the pairs of links 110 are connected to an actuator 114 by a pivot 115 and the actuator 114, carries the pin 116 of a pair of sheaves 107 and 108. The mounts 111 of each mandrel section 30E have shoulders 117 defining marginal stops limiting the extent to which the actuator may swing. Stops 118, see FIG. 21, are engageable by one set of actuator ends to limit their movement when the mandrel sections 30E are moved into their pile-entering relationship and stops 119 are engageable by the other set of actuator ends to limit the extent to which the toggle joint can be operated when the mandrel sections 30E are moved into their pile-gripping relationship, to prevent any binding, for example, when mandrel-expanding forces are released.

In the embodiment of the invention illustrated by FIGS. 24 and 25, spring means are provided to urge the mandrel sections into their pile-entering relationship and parts that correspond to those of other embodiments are distinguished by the suffix addition "F" to the appropriate reference numerals.

The spring means are shown as associated with the toggle joint 33F but they may be associated with operating means of the type employed in the expandible mandrels of the type illustrated by FIG. 1 in lieu of the retracting means described for use therewith or for the

retracting means in the embodiments illustrated by FIGS. 20 and 27. It will be apparent that the spring means, illustrated in FIGS. 18 and 19 as parts of connecting means, may also be used to effect the pile-gripping relationship of the bottom ends of the mandrel sections.

In FIGS. 24 and 25, the mandrel sections 30F have lengthwise reinforcements 82F and are connected by a toggle joint 33F shown, for convenience, as identical to the toggle joint 33 detailed in connection with FIGS. 3 - 6.

The reinforcements 82F, first at one side of the assembled mandrel and then the other, have sockets 120, each opening through the mandrel section of which it is a part. The sockets 120 are transversely aligned and have aligned bores 121 for a rod 122 extending into each socket 120 with retainers 123 backed as by nuts 124 threaded on the ends of the rod 122, each confining a compression spring 125 against the bottom of a socket. The spring means just described are spaced from each other lengthwise of the mandrel as required to provide adequate retracting force.

The embodiments of the invention illustrated by FIGS. 26 - 29 are generally similar to that shown in FIG. 20 and corresponding parts are distinguished by the suffix addition "G" to the appropriate reference numerals.

The mandrel sections 30G are connected by a toggle joint-sheave unit 33G at their bottom ends. This unit is not detailed as it may be similar to that shown and described in connection with FIGS. 16 - 18, except that, instead of a single sheave, there are double sheaves 71G.

The mandrel sections 30G are interconnected by operating means 36G consisting of a lengthwise series of pairs of toggle joint-sheave units similar to the arrangement shown and described in connection with FIG. 20, that is, the toggle joints of each pair are disposed so that when their sheaves are moved towards each other, the mandrel sections 30G are urged into their pile-gripping relationship. The toggle joint-sheave units of the operating means 36G are not detailed as they may be of the type shown and described in connection with FIGS. 21 - 23 except that each has two coaxial sheaves 110G.

The cable 35 extends downwardly about one of the sheaves 71G, see FIGS. 26, 27, and 28, and then about appropriate ones of the sheaves 110 of each pair of toggle joint-sheave units in the same manner as in the case of the mandrel shown and described in connection with FIG. 20 and is then connected to actuating means such as the fluid pressure operated means shown in FIGS. 1, 2, and 20.

The cable 34G see FIGS. 26A, 27, and 28, is first trained about a second sheave 71G, then about the one of the proximate sheaves 110G of the proximate pair of toggle joint-sheave units, then about the third sheave 71G and then upwardly and trained about the proximate sheaves 110G of the remaining pairs of toggle joint-sheave units.

With this arrangement, the same toggle joints are actuated by the two cables but in different combinations and in opposite directions as will be apparent from a comparison of FIGS. 26 and 26A.

A different mandrel construction is illustrated by FIG. 29 in which each of the mandrel sections is shown as having a pair of laterally spaced members 126 of

rectangular section to which the links of the toggle joints are pivotally connected. A lengthwise arcuate member 127 is welded to each of the members 126 to interconnect them and an arcuate margin member 128 is welded to each of the members 126. The marginal members 128 and the members 127 are arcuate with respect to a common center and each marginal member includes an inturned flange 129 with the flanges 129 in the completed mandrel section 30G being coplanar. In practice, the corner of each member 126 separates the welds joining the members 127 and 128 and projecting corner portions are removed.

Reference is now made to FIG. 1C wherein an example is shown of a desired force distribution lengthwise of the mandrel with the force decreasing towards the upper end thereof. While this distribution is shown with a decreasing number of sheaves, the distance between the groups is also variable to achieve or contribute to that force distribution as by decreasing the distance between them in the case of the first type operating means or by increasing the distance between the toggle joints of each pair in the case of expandible mandrels of the second type.

In the embodiment of the invention as thus far described, the flexible means has been disclosed as cables. In subsequently described embodiments, other types of flexible means are shown in conjunction with other expandible mandrels of the first type and corresponding parts will be distinguished by the addition of appropriate different letters thereto.

The expandible mandrel illustrated by FIG. 30 has its parts that correspond to previously described mandrels distinguished by the suffix addition "H" to the appropriate reference numerals. The mandrel sections 30H are interconnected at their upper ends by a drive head generally indicated at 32H provided with a mandrel receiving seat 130 having an axial depending bolt 131 with a cross bar 132 connected thereto. The bolt 130 is axially movable and is backed by a compression spring 133. The upper end 134 of each mandrel section 30H has a slot 135 traversed by a head pin 136 extended through a slot in a link 137. The links 137 are pivotally connected to the cross bar 132 and the slots 135 also serve as passageways for air or hydraulic lines 138 and 139 for the fluid pressure operated piston-cylinder units 55H. With this type of head-to-mandrel connection, the mandrel sections are urged towards their collapsed position when the head is raised.

In this embodiment of the invention, there are a plurality of independent operating means for effecting the pile-gripping relationship of the mandrel section 30H of operating means, generally indicated at 36H and spaced lengthwise of the mandrel from each other. In this embodiment, the flexible means are roller chains 35H having relatively large size rollers, each chain connected to a head 140 on the rod or stem 60H of the piston-cylinder unit 55H and trained about members 73H and 74H in the manner characteristic of first type expandible mandrels. Each piston-cylinder unit 60H is suspended by a lashing 141 from hangers 142, one for each mandrel section 30H and welded thereto. The other end of each chain 35H is secured to an anchor 143.

In the disclosed embodiment, the lower two operating means 36H are shown as identical while the upper operating means includes two groups of the members 73H and 74H and hence its hydraulic piston-cylinder

unit 55H must provide a longer stroke. As a consequence, the two lower operating means become effective ahead of the upper one. If it is desired to have the grip of the expandible mandrel initiate at its lower end and progress continuously towards the upper end, the inlet orifices of the cylinder of the units 55H may be of different sizes, the orifice sizes of the bottom cylinder being the largest, the orifice of the upper cylinder being the smallest, and the orifice of the intermediate cylinder being of an intermediate size.

In this embodiment of the invention, each of the lower two heads 140 has links 144 pivotally connected thereto and provided with transverse arms 145 entrant of slideways 146 so dimensioned that as the stems 60H of each power operated unit 55H returns in a chain-relaxing direction, the arms 145 seat in the closed end of the slideways and then draw the mandrel sections into their pile-entering and removing relationship.

The members 73H and 74H may be seen in FIGS. 31 - 34. It will be noted that the mandrel sections 30H have lengthwise reinforcements 82H that are right angular in cross section thus providing passageways and spaced to provide intermediate channels. As the members 73H and 74H are similar a description of one will suffice. The carrier for each of the members consists of a pair of arcuate seats 147 in the bottom of each channel and in support of circular plates 148 which extend into the opposite channel and support a pin 149 in support of a sleeve which is the member 73H and it provides a degree of self-alignment.

The embodiment of the invention illustrated by FIGS. 35 - 38 is one also utilizing roller chains indicated at 35I and having large concave rollers. In this and subsequent embodiments of the invention the lower end of the flexible means is anchored to the mandrel and the upper end thereof secured to the stem of the fluid pressure operated means.

The members 73I and 74I are balls and the carrier for each is a socket 151 welded to the bottom of the appropriate mandrel section 30I in the channel established by its reinforcements 82I and having sides 152, projecting and extending into the opposite channel even when the mandrel sections are in their pile-gripping relationship, see FIG. 38.

The chain 35I is in trained engagement with the balls 73I and 74I and extends between guides 153 spaced from the sides of the channels to provide space for hydraulic or air lines. The guides are cut away as at 153A to accommodate the balls as the mandrel sections are forced into their pile-gripping relationship and to supplement the socket portions 151A in providing ball retaining means in both lengthwise directions while permitting the lengthwise passage of the chain 35I.

Each socket 151 has an axial bore 154 for a follower 155 backed by a spring 156 so that the chain 35I is kept taut in the event the mandrel is stuck in its expanded position with the chain tension relaxed.

The members 73J and 74J shown in FIGS. 32 - 42 consist of arcuate sheave portions secured between the sides 157 of a tubular carrier 158 of rectangular cross section. Each carrier 158 is slidable seated in a socket 159 welded in place in the appropriate mandrel section 30J which are otherwise similar to the sections 30I of FIGS. 35 - 38. The sides 157 extend forwardly and rearwardly and support rollers 160 retaining the cable 35J in contact with the fixed sheave members.

In the embodiment of the invention illustrated by FIGS. 43 - 46 parts corresponding with those of preceding detailed embodiments are distinguished by the suffix addition "K" to the appropriate reference numerals.

The mandrel sections 30K of this embodiment have a wall thickness such that reinforcements are unnecessary. The members 73K and 74K are identical and each consists of a spherical rim 161 and a central web 162 with the arcuate cross section of the rim being such as to fit the interior of the mandrel sections as will be apparent from FIGS. 45 and 46. Each rim 161 has a central groove 163 for the chain 35K.

A group of the members 73K and 74K is shown in FIGS. 43 and 44. The end members of each group are welded to the appropriate mandrel section while the intermediate members are free to move lengthwise thereof when the chain 35K is relaxed and to return to position when the chain is again pulled to force the section into gripping relationship with the pile.

In the embodiment of the invention illustrated by FIGS. 47 and 48, the flexible means consists of wire rope 35L and the members 73L and 74L are multi-grooved sheaves rotatably supported by carriers 165 seated in sockets 166 welded in place in the mandrel sections 30L and provided with individual reinforcements 167. As the group of members is the bottom group, the bottom member 73L serves as an anchor about which the rope is trained and is provided with braces 168. A lead sheave 173L serves to center the wire rope towards the next group of members.

If preferred, the carrier 169 of FIG. 49 may be used. The carrier 169 consists of a relatively thick plate in support of the shaft 170 whose end portions support separate grooved sheaves 173L for the wire rope and whose braced socket 171 slidably receives it.

In FIG. 50, the flexible means is in the form of a reinforced belt 35M and the members, the member 73M, for example, is in the form of a pulley whose shaft 172 is supported by a carrier 173 slidably seated in a braced socket 174.

In FIGS. 51 and 52, the flexible means again consists of a series of wire ropes 35N and these are trained about arcuate, multi-grooved, sheave portions 73N, 74N each having side plates 175 secured thereto in support of a resiliently flexible pin 176 extended freely through a carrier plate 177 welded to the appropriate mandrel sections 30N and to lateral braces 178. The upper end of the carrier plate 177 is rounded and fits freely within the arcuate inner surface of the sheave connected thereto. The ends of the wire ropes 35N are secured about a transverse anchor 179 held by a braced mount 180.

In the embodiment of the invention illustrated by FIGS. 53 and 54, the flexible means are shown as two heavy duty chains 35P, crane chains for example, and the members 73P and 74P are sheaves.

At their lower ends, the crane chains are connected to an anchor 181 having slots 181A to receive end links of the two chains which are secured therein by anchor pins 182 with the slots 181A disposed so that the links of both chains define an X in their trained engagement with the sheaves. At their upper ends, the chains 35P like the flexible means of the embodiments illustrated by FIGS. 30 - 52, are secured in any convenient manner, see FIG. 30, to the stem of a fluid pressure oper-

ated unit by which they are subjected to an operating pull.

Each of the sheaves 73P, 74P has a channel 183 for each chain and each channel has a central, V-shaped crest 183A which subdivides it for the reception of the two series of links of the chain in trained engagement therewith. The chains are desirably longitudinally offset, see FIG. 53, so that corresponding links of the two chains are not transversely aligned.

- 10 The sheaves 73P and 74P have carriages 184 and 184A, each welded to the appropriate mandrel section 30P and to a diaphragm plate 185 with which each mandrel section is provided and which are so disposed relative to each other that between the groups of members, the chains may pass therebetween. Each diaphragm has cutouts, one for each sheave of one series and one to freely accommodate each sheave of the other series. Each sheave carriage 184 or 184A is seated in a first mentioned cutout and welded to its diaphragm and to the mandrel section to which that diaphragm is welded. In order that the chains 35P may pass to and from each group, each group has end guide sheaves 186, only one being shown in FIG. 53 as the group of members is the lowermost group.
- 15 20 25 The carriages 184A are shown as having yokes 184B to receive the pins 187 in support of the sheaves. The yokes 184B have braces 184C and are interconnected by pin-retaining bolts 184D. As a means for holding the chains (or other flexible elements) in trained engagement with the sheaves (or other rotatable members) the members may be magnetic in which case their supporting pins are bronze.

30 35 40 It will be appreciated that the amount of welding required in manufacturing the expandable mandrels has a bearing on production costs and that stresses resulting from welding have a bearing on their strength. Subsequently described embodiments of the invention feature expandable mandrels in which welding is largely limited to their attachment to the heads and to the attachment to them of their end plates.

In the embodiment of the invention illustrated by FIGS. 55 - 58, the mandrel sections are indicated at 30Q and the operating means include a cannister consisting of sections 188, one for each mandrel section and shaped and dimensioned to nest therein. Each cannister section 188 has a bottom end plate 189 secured thereto and an end plate 190 welded to its upper end. The end plates 189 rest on the end plates 191 of the mandrel sections 30Q while each of the mandrel sections has a centering ring section 192 welded thereto. Resilient bumper sections 193 are confined between the end plates 190 and the centering section 192.

The end plates 190 are provided with anchors 194 for the ends of a suspending chain 195 trained about a sprocket 196 mounted on a pin 197 supported by links 198 which also support a pin 199 pivotally securing the upper end of a piston-cylinder unit 55Q. The stem or rod 60Q of the unit 55Q has a yoke 200 attached thereto by a pivot 201 and supporting the pin 202 of a sheave 203.

65 60 While the members and the flexible operating means may be any of those previously described, they are shown as multi-grooved sheaves 73Q and 74Q, each connected by a pin 204 to a carrier 205 welded in place lengthwise of the appropriate cannister section 188 and braced as at 206. Each carrier 205, except for the upper one of each group, desirably has a guide roller

207. The group of members shown in FIG. 56 is the bottom group and the flexible means is a wire rope 35Q trained about the sheave 203 and the bottom sheave 74Q and in trained engagement with the intermediate sheaves in the manner characteristic of first type expandable mandrels. The cannister sections 188 are shown as having ports 188A and 188B spaced and arranged so that each port of one cannister section overlies a sheave or a guide roller of the other cannister section.

It will be noted that the cannister sections 188 include marginal reinforcing guides 208 extending for the full length that the sheave 203 travels when the unit 55Q is operated and that the yoke 200 includes marginal flanges 200A engageable therewith in the relaxed relationship of the cannister sections and a key portion 200B entrant of a channel defined by the guides 208 of one cannister section thus to hold the sheave 203 against turning or shifting out of position.

While the cannister section involves welding, the strength of the mandrel sections 30Q are not affected. As there is no positive connection between the mandrel and cannister sections, other means are necessary to ensure the return of the mandrel sections into their pile-entering relationship. Such means may be of the type disclosed in FIG. 24. It is also desirable to prevent the cannister sections from turning relative to the bottom end of the mandrel and for that purpose the bottom end plates 191 are provided with key portions 191A entrant of slots 189A in the cannister end plates 189.

The embodiment of the invention illustrated by FIGS. 59 and 60 is also a first type expandable mandrel whose operating means includes a cannister whose sections 188R are shaped and dimensioned for nesting engagement with the mandrel sections 30R. In this embodiment, the members 73R and 74R are double sprockets rotatably supported by pins 210 mounted in carriers 211 each welded to an appropriate one of the cannister sections. The flexible means 35R consists of a pair of roller chains secured to an anchor 212 at the bottom end of the cannister. As a mandrel in accordance with this embodiment does not differ from that of FIGS. 55 - 58 it will not be further detailed other than to note that the other ends of the chains 35R are fastened directly to the stem of the piston-cylinder unit employed to exert an operating pull.

The embodiment of the invention illustrated by FIGS. 61-64 represents the preferred construction of the expandable mandrel with diaphragm plates 185S welded to the edges of the mandrel sections 30S. Boot sections 97S are welded to the lower ends of the mandrel sections 30S and each mandrel section has a flange section 231 welded thereto to which the flange 214 of the generally indicated head 32S is secured by bolts 215.

The members 73S and 74S are multi-grooved sheaves each rotatably mounted in a carrier 216. The diaphragm plates 185S are cut away to accommodate all the members of each group with the carriers 216 in force-applying relationship with the appropriate mandrel section 30S. Links 217 between the carriers 216 of each series of members of a group are pivotally connected thereto and the proximate carriers of each series in proximate groups have longer links 218 pivotally connected thereto, the length of the links 218 depending on the desired spacing of the groups of members

lengthwise of the mandrel. The uppermost carriers 216 of the uppermost group are suspended by links 219 pivotally connected thereto and anchored by pins 220, one for each mandrel section and located adjacent the upper end thereof. The lowermost carriers 216 of the bottom group of members are secured by links 221 and 221A to anchors 222, each connected to the appropriate one of the end plates 223 of the boot sections 97S. As shown in FIG. 62, each anchor 222 extends freely into a bore 223A in an end plate 223 and is provided with a head 224 with which a compression spring 225, backed by a retainer 226, is in engagement thus tensioning the suspended structure.

The connecting means 35S are shown as comprising a series of wire ropes, shown as four in number. As may be seen in FIGS. 61 and 64, each wire rope has a clevis eye end portion 227 connected by a common pin 228 to a T-shaped anchor 229 seated in a bore 230 in one end plate 223 and secured by an anchor pin 231. The wire ropes 35S are trained about the sheaves 73S and 74S and in the manner characteristic of first type mandrels and then are trained about the multi-grooved sheave 232 rotatably supported by links 233 pivotally connected to the head 234 of the stem 60S of the fluid pressure operated, piston-cylinder unit 55S. A multi-grooved sheave 235 is rotatably supported by one of the diaphragm plates 185S and pairs of wire ropes 35S are then oppositely trained about and secured to the sheave 235 to equalize the pull thereon.

It will be noted that one boot section 97S includes a key portion 236 slidable entrant of a keyway 237 in the other boot section thus preventing misalignment of the mandrel sections 30S.

An important feature of the invention illustrated by FIG. 61 is that the wedge sections 238 are anchored between the flange sections 213 and the head flange 214 by the bolts 215. The size of the wedge section is exaggerated as it will be appreciated that on the scale of FIG. 61, the mandrel being sixty feet or more long, the wedge sections 238 and their function will not be readily apparent. From FIG. 61, it will be apparent that as the bolts 215 are tightened, the mandrel sections 30S are biased towards and against each other providing a normal pile-entering relationship.

The resilient means previously disclosed, see FIGS. 18 and 19, could also be used in effecting the pile-entering relationship of mandrel sections.

The embodiment of the invention illustrated by FIGS. 65-67 is also one where the members 73T and 74T are multi-grooved sheaves with the carriers 216T interconnected by chains instead of links with only the chains 239 interconnecting the carriers 216T of both series of members of the bottom group being shown. The lowermost carriers of that group are connected by chain lengths 240 and 240A to anchors 241, one for the plate 223T of each boot section 97T and welded thereto. Each plate section 223T is provided with a transverse channel providing a shoulder 242 and each anchor 241 has a transverse channel 243 caught thereby. The suspending chains, not shown, may be secured to the upper ends of the mandrel section in the manner shown in FIG. 61.

The flexible means 35T are wire ropes as in the case of the mandrel of FIGS. 61 - 64 and are secured to one of the anchors 241 by a pin 244.

One plate section 223T has a key portion 236T slidably entrant of a keyway 237T with which the other

plate section 223T is provided. The boot sections 97T are shown as interconnected by means generally indicated at 245 resiliently urging them into their pile-entering relationship, the means 245 being of the type illustrated by FIGS. 24 and 25.

In FIGS. 68 and 69, an embodiment of the invention is shown with the members 73U and 74U suspended within the mandrel sections 30U. In this embodiment, the members of each group are all supported by common mounts 246 with the mounts interconnected to corresponding mounts of the other groups and to the ends of the mandrel sections by chains 239U. Each mount 246 has transversely aligned slideways 247 for the carrier 249 to which the members of both series are rotatably connected. The mandrel of FIGS. 68 and 69 may be otherwise like the mandrel previously detailed of the suspension type.

Reference is now made to FIGS. 70 and 71 in which a preferred mounting of the members of a mandrel is shown, the mandrel having its sections 30V in accordance with the construction illustrated by FIG. 61. Each section 30V has a diaphragm 185V welded to its edges and each diaphragm has cutout areas, generally indicated at 249, one for each group of members 73V and 74V, shown as sheaves. In each area, mounts 250, conveniently lengths of right angular stock, are welded to each side of both mandrel sections. The mounts 250 of each section have transversely aligned pairs of bars 251 welded thereto with the bars of each pair spaced to define a seat for a carrier 252 for one series of sheaves 73V or 74V, and with the pairs of bars 251 spaced from each other to accommodate the sheaves of the other series.

From the foregoing, it will be apparent that expandable mandrels in accordance with the invention are well adapted to meet a wide range of requirements both in production and in use. It should be again noted that one of the important features of the invention is that it enables mandrels to have the expanding forces related to earth pressure as the deeper the pile penetration, the greater the earth pressure. It is desirable to have the expanding force increase from the upper end towards the lower or boot end of the mandrel in approximate relation to the increase in earth pressure. The objective is attained by the spacing of the groups of members, by the number of members in the groups, and desirably by combinations of both approaches. The closer the group spacing and the greater the number of members in a group both contribute to greater expanding forces.

We claim:

1. An expandable mandrel for use in driving or withdrawing tubular members such as piles, tubes, pipes and the like, said mandrel comprising sections, a head connected to and joining the upper ends of the sections, said sections being shaped and dimensioned so that they may move towards and away from each other to have a first relationship in which the mandrel may be entered in a tubular member of a predetermined cross sectional size and shape and a second relationship in which the sections grip interior surfaces of the entered tubular member, and at least one means operable to effect such movement of the sections, said means including a flexible element extending lengthwise of the interior of the mandrel and a plurality of units within and spaced lengthwise along the interior of said mandrel, each unit including a member, and said units being so incorporated in said mandrel relative to its sections and

the flexible element being so trained relative to their members that on a pull on the flexible element in one direction, said units subject said sections to opposite transverse forces that are operable to urge the sections 5 relative to each other into one of said relationships.

2. The expandable mandrel of claim 1 in which said one relationship is the pile-entering relationship.

3. The expandable mandrel of claim 1 in which said one relationship is the pile-gripping relationship.

4. The expandable mandrel of claim 1 in which the members are arranged in two series and the trained engagement of the flexible means therewith moves the members in opposite directions.

5. The expandable mandrel of claim 1 and second 15 flexible means common to the members and in such trained engagement therewith that the members are moved, in response to a pull thereon, in a direction opposite to that resulting from a pull on the first named flexible means, to transmit opposite transverse forces 20 on the mandrel sections urging them into the other of their relationships.

6. The expandable mandrel of claim 1 in which a fluid pressure operated unit is supported by the mandrel within its upper part and connected to the flexible 25 means to effect an upward pull thereon.

7. The expandable mandrel of claim 6 in which the head includes a receiver attachable to a hammer and provided with a marginal flange and axial neck to which the fluid pressure operated unit is connected, a cap connecting the upper end of the mandrel sections through which the neck extends, and an annular member fitting the neck and interposed between the flange and the cap, a series of keepers overlying the flange and resting on the annular member, and bolt means connecting the cap and the keepers through the annular member.

8. The expandable mandrel of claim 7 in which the bolt means includes, adjacent their ends, complementally concave-convex portions.

9. The expandable mandrel of claim 8 in which the head includes a neck entrant of the upper end of the mandrel, a first backing part fixed on the neck, a second backing part pivotally connected to the fluid pressure operated unit, and lashing interconnecting the 45 backing parts.

10. The expandable mandrel of claim 5 in which corresponding ends of both flexible means are anchored to a mandrel section, a fluid pressure operated, piston-cylinder unit is supported by the mandrel between the 50 sections adjacent the head, the other end of one flexible means connected to the unit to be subjected to a pull when the unit is operated and the mandrel having a laterally disposed opening adjacent the head through which the other end of the other flexible means extends to enable it to be connected to a power device located externally of and above the mandrel capable of exerting an operating pull thereon.

11. The expandable mandrel of claim 10 in which the 55 mandrel opening through which the other flexible means extends has a pair of rotatable elements spaced lengthwise of each other through which said other flexible means is trained, the two rotatable elements being disposed to define the opening.

12. The expandable mandrel of claim 1 and a toggle joint connecting the mandrel sections at their lower ends and disposed, when actuated in a predetermined direction to urge the lower ends into one of the two re-

lationships, an actuating member between the sections, one end of the actuating member being connected to the toggle joint, a sheave connected to the other end of the actuating member, and the flexible means is an element trained about the sheave to exert a pull thereon in the predetermined direction.

13. The expandible mandrel of claim 12 and resilient means between the mandrel sections yieldably urging the bottom ends of the mandrel sections into the other relationship.

14. The expandible mandrel of claim 12 in which the flexible element is the element in trained engagement with the members of the operating means.

15. The expandible mandrel of claim 12 in which the relationship into which the mandrel sections are urged by the flexible element is the pile-gripping relationship.

16. The expandible mandrel of claim 15 and stop means operable to limit the extent to which the mandrel sections may be moved by the flexible element.

17. The expandible mandrel of claim 16 in which the actuating member has a transverse plate intermediate its ends, and the stop means comprises at least one stop carried by at least one of the mandrel sections for engagement with the plate.

18. The expandible mandrel of claim 17 in which each mandrel section includes internal reinforcements adjacent its edges marginally confining the plate of the actuating member and the stop means comprises one stop anchored to each reinforcement.

19. The expandible mandrel of claim 12 in which the actuating member includes a pivot between its ends.

20. The expandible mandrel of claim 12 in which the toggle joint includes a pair of links, a pivotal connection between each link and a mandrel section, the attaching means is in the form of a plate, and a pivotal connection between each link and the plate, one on each side of the mandrel axis.

21. The expandible mandrel of claim 20 in which the pivotal connections between the links and the plate are closer together than the pivotal connections between the links and the mandrel sections.

22. The expandible mandrel of claim 20 in which the pivotal connections between the links and the mandrel section in the pile-entering relationship thereof are spaced apart a distance less than the distance between the pivotal connections between the links and the plate, each pivotal connection between the links and the mandrel sections including a pivot pin, the plate having a pair of holes, one for each pivot pin and so dimensioned and disposed that its margins function as a section-spreading cam until the links are parallel.

23. The expandible mandrel of claim 1 and a toggle joint connecting the bottom ends of the mandrel sections and including an actuator and a sheave carried by the actuator, the flexible means is an element trained about the sheave with a course in trained engagement with the members including portions on both sides of the mandrel axis and with a course extending upwardly lengthwise of the mandrel, the sheave being diagonally disposed to position the last named course wholly within one mandrel section but at one side of the portions of the other course that are within that section.

24. The expandible mandrel of claim 23 in which the course that is wholly within one mandrel section is anchored to the upper end thereof and power operated

means are connected to the upper end of the other course.

25. The expandible mandrel of claim 1, and springs spaced lengthwise of the mandrel and attached to the mandrel sections and operable to yieldably urge the mandrel sections into their other relationship.

26. The expandible mandrel of claim 14 in which the relationship established by the springs is the first or pile-gripping relationship.

10 27. The expandible mandrel of claim 14 in which the relationship established by the springs is the second or pile-entering relationship.

15 28. The expandible mandrel of claim 14 in which each mandrel section includes lengthwise reinforcements, the reinforcements of the two sections include transversely aligned sockets spaced lengthwise of the mandrel, and the springs are confined in the transversely aligned sockets.

20 29. The expandible mandrel of claim 1 in which the members are sheaves, the force-transmitting connections are toggle joints and each includes means connecting a sheave thereto, and the flexible means is an element trained about the sheaves to effect a joint actuating pull thereon.

25 30. The expandible mandrel of claim 29 in which the toggle joints are arranged in oppositely disposed pairs establishing two series of members and the flexible element is trained about the sheaves of each pair of toggle joints to urge them towards each other on a pull on the element to urge the mandrel sections into one of said relationships.

35 31. The expandible mandrel of claim 30 in which the distance between the toggle joints increases towards the upper end of the mandrel.

32. The expandible mandrel of claim 30 and a second flexible element trained about the proximate sheaves of proximate pairs of toggle joints to urge them towards each other on a pull on the second element to urge the mandrel sections into the other of said relationships.

33. The expandible mandrel of claim 29 in which the connecting means is an actuating member.

34. The expandible mandrel of claim 33 and vertically spaced stops fixed on the mandrel sections and engageable by opposite ends of the actuating member to limit their movement lengthwise of the mandrel.

35. The expandible mandrel of claim 33 in which there are a pair of transversely spaced side supports for each toggle joint secured in each mandrel section, the support of each pair having transversely aligned pockets at one end opening through their edges that are proximate to the other pair of supports and extending downwardly and outwardly towards their other ends, the toggle joint includes at least one pair of arms, a pin for each arm and supported in the appropriate pockets, and a pin connecting the other ends of the arms and the actuating member.

36. The expandible mandrel of claim 33 in which each toggle joint includes side supports carried by the mandrel sections and engageable by the actuator to limit the extent to which it may swing.

37. The expandible mandrel of claim 33 in which there is a pivoted connection between each toggle joint and the actuator and each connecting means includes stops limiting the extent to which each actuator may swing.

38. The expandible mandrel of claim 32 in which a bottom toggle joint connects the bottom ends of the

mandrel sections, the bottom toggle joint includes an actuator extending towards the other end of the mandrel and has a sheave, the flexible element by which the pile-gripping relationship of the mandrel section is established extends downwardly in the mandrel and about the sheave of the bottom toggle joint and then about both sheaves of each pair of toggle joints, and the flexible element by which the pile-entering relationship of the mandrel sections is established is first trained downwardly about the sheave of the bottom toggle joint, then about the proximate sheave of the proximate pair of toggle joints, and then again about the sheave of the bottom toggle joint.

39. The expandible mandrel of claim 1 in which the members are arranged in two series, one series of each mandrel section, the members being arranged in groups in which the members of one series alternate with those of the other series, the groups being spaced lengthwise of the mandrel, the trained engagement of the flexible means is with the members of each group in succession, and the members are so disposed transversely of the mandrel sections and so dimensioned that the trained engagement of the flexible means is sinuous whereby the sections are forced into one of said relationships as a pull on the flexible means straightens it.

40. The expandible mandrel of claim 39 in which the portion of each member of the series of each mandrel section with which the flexible means is in trained engagement extends into the other section and the relationship resulting from a straightening pull is the pile-gripping relationship.

41. The expandible mandrel of claim 39 in which the portion of each member of the series of each mandrel section engaged by the flexible means is within its mandrel section and the relationship resulting from a straightening pull is the pile-entering relationship.

42. The expandible mandrel of claim 39 in which the members are rotatable with the members of each series dimensioned to provide portions in both mandrel sections.

43. The expandible mandrel of claim 42 in which the axes of the rotatable members of each series are located above the plane inclusive of the edges of the mandrel sections of that series.

44. The expandible mandrel of claim 39 and second flexible means trained successively about the members in a manner opposite to that of the first named flexible means whereby a pull on the second flexible means forces the mandrel sections into the other of said relationships.

45. The expandible mandrel of claim 39 in which the numbers of members in each group decreases towards the upper end of the mandrel.

46. The expandible mandrel of claim 39 in which the distance between the groups increases towards the upper end of the mandrel.

47. The expandible mandrel of claim 1 in which the relationship established by the pull on the flexible means is the first or pile-gripping relationship and the members are spaced and arranged lengthwise of the mandrel and relative to each other to provide an expanding force distribution that is at a maximum adjacent the bottom end of the mandrel.

48. The expandible mandrel of claim 47 in which the spacing of the members results in a pile-gripping relationship and the members are spaced and arranged to

provide an expanding force distribution that is at a maximum adjacent the bottom end of the mandrel.

49. The expandible mandrel of claim 47 in which the spacing of the members results in a force being applied and the trained engagement of the flexible member is such that said force is progressively in time from the bottom of the mandrel to the upper end thereof.

50. The expandible mandrel of claim 1 in which each mandrel section is arcuate in cross section and includes 10 a pair of transversely spaced, internal, lengthwise reinforcements establishing a central channel, each unit being within the channels of both sections.

51. The expandible mandrel of claim 50 in which each reinforcement is right angular in cross section.

52. The expandible mandrel of claim 50 in which the reinforcements extend substantially the full length of the mandrel sections.

53. The expandible mandrel of claim 50 in which each unit includes a carriage seated in one channel with 20 portions entrant of the other channel and fitting between the reinforcements thereof.

54. The expandible mandrel of claim 53 in which each unit is anchored to the reinforcements between which it is seated.

55. The expandible mandrel of claim 39 in which each mandrel section is arcuate in cross section and includes a reinforcement in the form of a diaphragm plate extending substantially the full length of the mandrel adjacent its edge and each diaphragm plate has 30 openings for the members of each group.

56. The expandible mandrel of claim 55 in which each member includes a mount seated through one of its openings and anchored to the appropriate diaphragm.

57. The expandible mandrel of claim 55 in which each opening is dimensioned to accommodate all the members of the appropriate group, and means interconnect corresponding members of the groups under the diaphragms and the interconnecting means are secured to the upper and bottom ends of the mandrel sections.

58. The expandible mandrel of claim 57 in which each member includes a carriage and each mandrel section has a pair of mounts extending lengthwise of each opening and welded therein adjacent its edges, the mounts for each opening including transversely spaced pairs of bars defining seats, each slidably receiving and confining the carriage of a member of one series, and the pairs of bars are spaced lengthwise from each other to accommodate the members of the other series.

59. The expandible mandrel of claim 1 in which each mandrel section includes a pair of lengthwise, laterally spaced members to which the force-transmitting connections are attached, a lengthwise connecting member welded to and connecting the pair of laterally spaced members of each section, and a marginal member welded to each of the pair of laterally spaced members of each section, the connecting and marginal members all being arcuate with respect to a common center, and the portions of each section that are the junction between the arcuate members and the pair of laterally spaced members also being substantially arcuate with respect to said center.

60. The expandible mandrel of claim 59 in which the portions of each of the pair of laterally spaced members of each section that is exposed within that section are rectangular in cross section.

65

61. The expandible mandrel of claim 60 in which each of the pair of laterally spaced members of each section includes an outer portion separating the welds between the marginal and connecting members.

62. The expandible mandrel of claim 60 in which the marginal members of each section have inturned, transversely aligned flanges.

63. The expandible mandrel of claim 1 in which the operating means extends substantially the full length of the mandrel.

64. The expandible mandrel of claim 1 in which there is a plurality of operating means, each spaced lengthwise of the mandrel and each of the operating means includes a fluid pressure operated unit within and supported by the mandrel to which its flexible element is connected and by which an operating pull is effected.

65. The expandible mandrel of claim 64 in which said one relationship of each of the operating means is the pile-gripping relationship and each of the operating means includes means connected to the mandrel sections and operable to urge the mandrel sections into their pile-entering relationship.

66. The expandible mandrel of claim 64 in which each fluid pressure unit includes a stem having predetermined travel, and each of the means urging the mandrel sections into their pile-entering relationship includes a pair of arms pivotally connected to the stem of the appropriate one of the units to travel with the flexible element and each arm includes a connection with an appropriate one of the mandrel sections that is slidable while said stem is exerting said pull but is seated before the stem has fully returned then to urge the mandrel sections into their pile-entering relationships.

67. The expandible mandrel of claim 39 in which a fluid pressure operated unit is supported by the mandrel between upper end portions of the mandrel sections and includes a stem, a sheave is rotatably supported by the stem, one of the mandrel sections includes a sheave mounted therein in a fixed position between the uppermost group and the sheave of the unit, and the flexible means is anchored at one end to the bottom of one mandrel section and its upper end is trained about the sheave of the unit and anchored to the fixed sheave.

68. The expandible mandrel of claim 1 and a cannister within said mandrel and supported thereby, said cannister including sections, one for each mandrel section, the force-transmitting connections including the cannister sections.

69. The expandible mandrel of claim 68 in which the members of the operating means are within the cannister and connected to the cannister sections.

70. The expandible mandrel of claim 68 in which the lower end of each section of the cannister is supported by a seat on the appropriate one of the mandrel sections and each mandrel section includes a cannister-centering part overlying the upper end of a cannister section, and a resiliently yieldable bumper is disposed between each said upper end and the overlying part.

71. The expandible mandrel of claim 68 and means connecting each cannister section to the appropriate one of the mandrel sections to prevent the cannister section from turning relative to the mandrel section.

72. The expandible mandrel of claim 71 in which each mandrel section has a bottom plate and each can-

nister section has a bottom plate which seats on the bottom plate of the appropriate mandrel section, and a key and a keying connection between the appropriate mandrel and cannister plates.

73. The expandible mandrel of claim 39 in which the members include carriers, means interconnect the carriers of each series of members, and suspending means connect each series of interconnected carriers to an appropriate one of the mandrel sections with the carriers disposed for force-transmitting engagement therewith.

74. The expandible mandrel of claim 73 in which the mandrel sections include bottom plates and the suspending means are connected to the upper ends of the mandrel sections and the bottom plates.

75. The expandible mandrel of claim 74 in which the connections of the suspending means with the bottom plates are resilient.

76. The expandible mandrel of claim 73 in which the interconnecting means are flexible.

77. The expandible mandrel of claim 73 in which the interconnecting means are links pivotally connected to the carriers.

78. The expandible mandrel of claim 73 in which the interconnecting means include mounts for the members of each group, each member of each group being connected to its mount for movement transversely of the mandrel.

79. The expandible mandrel of claim 1 in which each mandrel section includes a bottom plate, and there is a key and keyway connection between the bottom plates.

80. The expandible mandrel of claim 39 in which each member of both series of each group of members protrudes from one of the mandrel sections into the other mandrel section and a carrier seated within the first named mandrel section in a force-transmitting relationship therewith, and a connection between said member and carrier.

81. The expandible mandrel of claim 80 in which each carrier also includes retaining means spaced from the member supported by that carrier and disposed to retain the flexible means in desired relation thereto when the tension thereon is relaxed.

82. The expandible mandrel of claim 80 in which each member is rotatably supported by its carrier.

83. The expandible mandrel of claim 80 in which each member is arcuate and presents a fixed surface with which the flexible means is in sliding contact.

84. The expandible mandrel of claim 80 in which the connection between each member and its carrier enables the member to move relative thereto transversely of the mandrel.

85. The expandible mandrel of claim 80 in which each member is a sheave and the flexible means is a cable.

86. The expandible mandrel of claim 80 in which each member is spherical and the flexible means is a roller chain whose rollers are concave.

87. The expandible mandrel of claim 80 in which each member includes a spherical rim having an annular groove receiving the flexible means.

88. The expandible mandrel of claim 82 in which each member is a sprocket and the flexible means is a chain.

89. The expandible mandrel of claim 82 in which each member has a pair of peripheral channels and the

flexible means comprise a pair of chains of the crane chain type, one for each channel and anchored to a mandrel section in such a manner that their links define an X in their trained engagement with the members, each channel including a central V-shaped crest subdividing it for the reception of the two series of links of an appropriate one of the chains.

90. The expandible mandrel of claim 89 in which each of the corresponding links of the two chains are longitudinally offset.

91. The expandible mandrel of claim 82 in which each member is a pulley and the flexible means is a belt.

92. The expandible mandrel of claim 82 in which each member is a multi-grooved sheave and the flexible means is a series of wire ropes.

93. The expandible mandrel of claim 82 in which the members and their connections are self-aligning.

94. The expandible mandrel of claim 82 in which the members are of magnetic stock, the carriers are of non-magnetic stock, and the flexible means are magnetically responsive.

95. The expandible mandrel of claim 84 in which each carrier includes a socket and a compression spring within each socket urges the member supported thereby towards the other mandrel section.

96. The expandible mandrel of claim 81 in which the connection is a resiliently flexible pin.

97. The expandible mandrel of claim 84 in which each carrier includes a socket and the member supported thereby includes a portion slidably entered within the socket.

98. The expandible mandrel of claim 95 in which each member is spherical, the carrier includes side portions confining that member and each mandrel section also includes means extending lengthwise confining the members of the other section against escape from their carriers and providing guides for the flexible means.

99. The expandible mandrel of claim 39 in which each member of both series of each group of members 40 protrudes from the mandrel section with which it is in force-transmitting relationship into the other mandrel section, the end members of each group are secured to the first named mandrel section and each intermediate member is free to move relative thereto in a direction 45 lengthwise of the mandrel.

100. The expandible mandrel of claim 83 in which each mandrel section, in the zone of each of the connecting means, includes a pair of lengthwise supports, pairs of transversely aligned ears, each ear attached to an appropriate one of said supports and protruding beyond the edges of the section to which it is attached, and each member is a sheave and includes a pin supported by a pair of ears.

101. The expandible mandrel of claim 100 in which the lengthwise supports of each mandrel section have transversely aligned lengthwise channels and frames, each frame including a pair of ears and marginal portions slidably confined by the channels.

102. The expandible mandrel of claim 101 in which the channels are straight.

103. The expandible mandrel of claim 101 in which the channels are arcuate.

104. The expandible mandrel of claim 100 in which the ears have transversely aligned bores dimensioned to slidably receive the sheave pin and the sheave pin slidably supports its sheave, the bores being spaced to en-

able a sheave pin to be inserted therethrough with the frame connected to the supports, the supports of each mandrel section including transversely aligned pin stops confining the ends of a pin of a sheave connected to the other mandrel section from objectionable axial movement.

105. The expandible mandrel of claim 100 in which each pair of ears has transversely aligned bores, a bushing is fitted in each bore and slidably receives the ends 10 of a sheave pin, each sheave is slidably supported by its sheave pin, the bores of each ear are located to be partly blocked by the supports to which they are attached and partly blocked, on the assembled mandrel, by the supports of the other section, one bushing including sections so dimensioned that with the pin in support of its sheave and with one pin end seated in the other bushing, and with the other mandrel section spaced to expose the portion of the bores it blocks when the mandrel is in use, the bushing sections can be 20 inserted one at a time into the bore and turned to support the other pin end.

106. The expandible mandrel of claim 105 in which each bushing has a shoulder at the outer end of its pin-receiving bore.

107. An expandible mandrel for use in driving or withdrawing tubular piles and the like, said mandrel comprising sections, a head connected to and joining the upper ends of said sections, and means operable to vary the spacing between pile-entering and pile-gripping relationships, said means including portions in force-applying relationship with said sections and means operable to provide an expanding force distribution on said portions that is at a maximum adjacent the bottom end of the mandrel and decreases towards the upper end to provide a substantially constant force in opposition to the pressure of the surrounding earth which increases in depth.

108. The expandible mandrel of claim 107 in which the expanding force is applied progressively in time from the bottom of the mandrel to the upper end thereof.

109. An expandible mandrel for use in driving or withdrawing tubular piles and the like, said mandrel comprising sections, a head, means connecting the upper ends of the sections to the head in a fixed spaced-apart relationship that biases the sections below the connecting means towards each other to establish a normal pile-entering relationship, and means between the sections and operable to force said sections apart into a pile-gripping relationship.

110. The expandible mandrel of claim 109 in which the connecting means include surfaces that are in mutual contact when the mandrel sections are connected to the head, one of the mutually engageable surfaces being inclined relative to the mandrel axis and to the other surface so that when the surfaces are in mutual contact, the mandrel sections are biased inwardly towards each other.

111. The expandible mandrel of claim 109 in which the head includes a flange, each mandrel section includes a flange at its upper end, an inwardly tapering wedge section is interposed between each section flange and the head flange, and clamping bolts interconnect the section flanges to the head flanges through the appropriate wedge section.
